UNITED STATES PATENT OFFICE.

ISAAC JOHNSON, OF CHICAGO, ILLINOIS.

IMPROVEMENT IN LIGHTNING-RODS.

Specification forming part of Letters Patent No. **170,377**, dated November 23, 1875; application filed January 19, 1875.

To all whom it may concern:

Be it known that I, ISAAC JOHNSON, of Chicago, in the county of Cook and State of Illinois, have invented a new, useful, and Improved Coupling for Tubular Lightning-Rods, of which the following is a full, clear, and exact description, which will enable others skilled in the art to which my invention appertains to make and use the same, reference being had to the accompanying drawing, forming a part hereof, and in which—

Figures 1 and 2 are side elevations of a tubular rod provided with my improved coupling, and Fig. 3 a like representation of the coupling detached.

Like letters of reference indicate like parts.

My object is to provide improved means for the purpose of coupling together the sections of tubular lightning-rods; and to that end my invention consists of a hollow and indented coupling-piece, open at both ends, and arranged substantially as hereinafter described with relation to correspondingly-indented sections of the rod.

In the drawing, A and A' represent sections of tubular lightning-rods. B is the coupling-piece. This piece is made tubular, and is of such a size and form that it may be easily inserted into the ends of the sections of the rod, and yet fit nicely therein. a a' are annular grooves cut or sunken into the part B.

In order to couple together the sections of tubular rods by means of the part B, I insert the latter into one end of a section until one of the grooves on the coupling is covered by the rod. I then swage the rod into the groove thus covered, employing for this purpose any suitable tool. This part of the operation is shown in Fig. 1, e representing the groove thus made in rod. In order to determine where the swaging-tool should be applied to the rod, both the coupling-piece and rod may be so marked that when the edge or end of the section reaches the mark on the coupler the mark on the section will be directly over the groove into which the rod is to be swaged. The proper position of the parts is clearly shown in Fig. 2. One end of

each section is thus provided with a coupling-piece, and the sections may be shipped in this condition.

When the rod is put up the open end of one section is arranged upon the projecting end of the coupling in another section, until the rod is thus made sufficiently long, each section being swaged into the grooves a or a' in the manner described. The appearance of the joint thus made is illustrated at e', Fig. 1.

The operation of coupling the sections in the manner described may be easily and rapidly performed, and with slight expense. The rod is not cut or weakened at any point, but is rendered stiffest and strongest at the joints, and the sections are firmly united. The rod is also of a uniform size.

It is frequently desirable to introduce solid rods within the tubular sections, the solid rods being continued past the joints of the tubular sections. By employing the tubular pieces B B, in the manner described, these solid rods may be readily introduced, and the water may also pass freely through the tubular part of the rod.

I am aware that solid coupling-pieces, having their outer surfaces corrugated to admit of the passage of water along the interior of the rod, have heretofore been employed for the purpose of uniting the sections of tubular rods, the coupling-pieces and sections being indented, and arranged substantially as described with relation to each other, and I do not here claim such; but,

Having thus described my invention, what I claim as new, and desire to secure by Letters Patent, is—

A tubular lightning-rod made in sections, and indented, substantially as described, in combination with the hollow and correspondingly-indented coupling-pieces B B, open at both ends, and arranged as shown with relation to the sections, substantially as and for the purposes set forth.

ISAAC JOHNSON.
